OPERATING MECHANISM FOR TURRET LATHES

William H. Foster, Elkhart, Ind.

Application December 16, 1929, Serial No. 414,417

20 Claims. (Cl. 29—42)

The invention relates to improvements in pressure operated mechanism and has reference more particularly to a novel fluid actuated device for association with hydraulic turret lathes.

5 An object of the invention is to provide an improved automatic operating mechanism for turret lathes, which will be adapted to meet the needs of commercial operation of such machines. Another object is to provide a fluid pressure operated mechanism for actuating turret lathes, which will serve to reduce to a minimum the time consumed between the completion of one operation upon a piece of work, and the starting of the next operation upon the same piece.

10 15 A further object is to provide improved hydraulic operated mechanism for controlling the movement of the turret slide, which will embody special features for allowing a more efficient indexing of the turret.

20 25 A yet further object is to provide an improved pressure actuated mechanism, preferably using oil as an operating medium, which will adapt itself for use in various ways as a source of power for actuating machinery, employing the minimum number of parts, and which will be positive and reliable in operation.

Still another object of the invention is to provide a fluid actuated mechanism adapted for imparting reciprocating movements to a turret slide which will allow for a rapid speed of the slide to take place in retracting the same up to the time indexing starts and which will then decelerate the speed to allow efficient operation of the parts for proper indexing. In addition, the mechanism 30 35 also allows for a rapid speed of the slide in its forward movement. This makes possible a maximum in speed both forward and retracting and at the same time provides for a speed consistent with the indexing cycle.

40 45 With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a sectional view taken substantially 50 through the center of the improved hydraulic operated mechanism constructed in accordance with the present invention.

Figure 2 is a rear elevation of a turret lathe showing hydraulic operated mechanism associated therewith.

The present invention is especially adapted for application to turret lathes of the type as disclosed in the applicant's co-pending application, Serial No. 352,427, filed April 4th, 1929, employing a turret slide 4 (Figure 2), having reciprocating movement upon the bed of the lathe 2, which serves to present the various tools 6 into position for operation upon the work piece. Upon the slide is rotatably mounted a turret 8 of the conventional type, common to all turret lathes and generally provided with a plurality of stations for holding in position the various tools. The turret slide is equipped with suitable mechanism for accomplishing the reciprocating movement upon the bed of the machine, which may be operated either manually or automatically. Inter-related with this mechanism and operating to rotate the turret are other means which are adapted to be brought into operation upon the rearward movement or retracting of the turret slide to rotate the turret one station or to index the turret as it is known. This presents a different tool in alignment with the work piece upon the chuck, whereupon the forward movement of the turret slide can then take place to bring the tool into contact with the work piece. It is seen therefore that part of the rearward movement of the turret slide imparts actuation to mechanism to index the turret, which necessarily requires a deceleration in the speed of the slide to allow an efficient operation of this indexing mechanism. However, the advancing movement of the slide can take place at the normal speed, as the indexing is complete when the extreme rearward movement of the slide is reached.

Referring to Figure 1, a cylindrical member 10 is disclosed comprising the cylinder of the mechanism and has fitted therein, a piston or plunger 12. The piston has provided on its bearing surface rings or suitable packing 14, which insure a perfect fit between the bearing parts, to prevent the pressure fluid from leaking past the piston. The piston has suitably secured thereto a piston rod 16, which is adapted to constitute the actuating means and as such is mechanically connected through means of the bracket 17 to the turret slide 4. The movements of the piston are in this manner imparted to the slide to cause the retracting and forward movements of the same. The cylinder 10 has secured thereto through suitable bolts 18 a closure member 20 comprising the right end of the cylinder and provided with an opening 22 for allowing exit of the piston rod 16. A collar 24 is adjustably secured to the closure member and is adapted 55

to maintain suitable packing 25 in contact with the closure member and the piston 16.

The cylinder 10 is closed at its end opposite the member 20 by a cylindrical member 26, having shoulder portions 28 for abutting the cylinder 10 and a reduced portion 30 adjacent the shoulder for insertion within the cylinder as shown. This construction in connection with suitable bolts serves to securely unite the member 26 to the end 10 of the cylinder in a manner to allow operation of the remaining mechanism to be presently described.

The member 26 is provided with a bore 32 extending substantially its entire length and of a 15 diameter smaller than the inside diameter of the cylinder 10. A tubular plunger 34 operates within the bore and is adapted to have a close fitting engagement therein, the surfaces of the bore and the outside surface of the plunger being 20 machined to exact dimensions. A spring 36 fits within the bore 32 and extends within the tubular plunger 34. The end wall 38 of the member 26 and the wall 40 of the plunger serve as bases 25 to limit the extension of the spring. For holding the plunger 34 within the bore 32 against the action of the spring, but at the same time to allow the plunger to have movement therein, a pin 42 is adjustably secured in the member 26 and a 30 groove 44 is provided in the plunger longitudinally thereof, ending however at 45. This allows the plunger to have reciprocating movement therein but prevents its release as the pin engages the end 45 of the groove. The action of the spring 36 tends to keep the plunger always in extended 35 position, that is, extending within the piston chamber defined by the cylinder 10.

Extending the entire length of the member 26 is a duct or passage 46 of small diameter the greater part of its length and of a somewhat 40 larger diameter designated 48 at the portion through the wall 38. Sloping sides 50 join the larger opening with the smaller and are adapted to have located adjacent thereto the pointed end 52 of the regulating screw 54. A passage 55 connects the opening 48 with the bore 32 so that any pressure fluid within the bore can be forced 45 through the restricted opening formed by the regulating screw 54 and be conducted into the piston chamber. By varying the size of the restricted opening, which is accomplished by screwing inward or outward the screw 54, the flow of fluid out of the bore can be regulated. Also related in operation to this structure are passages 56 and 58, formed in wall 40 of the plunger, which 50 also form a conduit from the bore 32 to the piston chamber. However, this means of escape for the pressure fluid is closed when pressure within the bore forces the ball 60 into engagement with its seat, thus closing passage 56. A spring 62 tends to hold the ball down against its seat, thus 55 constituting a check valve.

As previously explained the actuating fluid is forced under pressure into either pipe 64 located at the right end of the cylinder, or pipe 66 located at the opposite end, by means of a control valve depending on whether the turret slide is to be retracted or moved forward into cutting position. Assuming for the purpose of illustration that the turret slide is to be retracted to index a turret one station, oil which preferably forms the pressure fluid, is therefore forced under high pressure into pipe 64 and into the piston chamber to the right of the piston 12, thus forcing the piston to the left, as viewed in Figure 1. 70 The piston has opportunity to acquire a rapid

speed up to its engagement with the plunger 34, which thus allows the slide to have a rapid reTRACTING movement for part of its stroke, until it begins to index as described. For this the speed of the piston must be cut down, which is accomplished by movement of the plunger 34 to the left. The oil within the bore 32 and the hollow portion of the plunger is put under compression which consequently closes the check valve 60 and allows the oil to escape only through the restricted opening 50. The size of opening 50 is so regulated that the necessary decrease in speed of the piston 12 can be accurately secured. 75

The piston upon reaching the end of its stroke in its travel toward the left is then forced back 15 again by oil under pressure issuing from pipe 66, the supply in pipe 64 being cut off.

The plunger, however, with the piston in its left hand position is located within the bore 32 and is forced out by spring 36 as soon as piston 12 moves to the right. Valve 60 is so constructed that pressure on the outside will unseat the ball allowing the oil to flow within the plunger and the bore. During this movement of the piston 12, that is, to the right as viewed in Figure 1, the piston will have an unrestricted course and will so attain a rapid speed giving to the turret slide consequently a rapid speed for its forward movement. 20

It is to be understood that I do not wish to be 30 limited by the exact embodiment of the device shown, which is merely by way of illustration and not limitation, as various and other forms of the device will of course be apparent to those skilled in the art without departing from the 35 spirit of the invention or the scope of the claims.

I claim:

1. In a device of the class described, in combination with a movable member, of fluid pressure means for operating said member, said fluid pressure means comprising a cylinder, a piston operating within said cylinder, conduits having access to said cylinder to supply a fluid under pressure selectively to the two sides of said piston, and a plunger journaled in a wall of said cylinder at 45 one side of said piston adapted to be moved by said piston when said piston is adjacent to one end of its stroke, said cylinder having a restricted passageway therethrough providing communication between the two ends of said plunger to cause a decrease in speed of said piston adjacent to said end of the movement of said piston.

2. In a device of the class described, in combination with a movable member, of fluid pressure means for operating said member, said fluid pressure means comprising a cylinder, a piston operating within said cylinder, a plunger journaled in a wall of said cylinder normally extending within said cylinder and adapted to be engaged by said piston to cause a decrease in the speed of the 60 piston in one direction of movement, said cylinder being provided with a restricted passageway providing communication between the two ends of said plunger. 55

3. In a device of the class described, in combination, a cylinder, a piston operating within said cylinder, conduits connected to said cylinder to admit a pressure fluid to opposite sides of said piston, a bore provided within one wall of said cylinder and extending axially thereof, a plunger 70 operating within said bore, means for allowing ingress of the fluid within said bore during one direction of movement of said piston and other means to regulate the escape of said fluid during the opposite direction of movement. 65

4. In a device of the character described, in combination, a cylinder provided with end walls forming a chamber, a piston operating within said chamber, means for supplying a pressure medium selectively to both sides of said piston, a bore in one end wall of said cylinder, a plunger fitted within said bore and extending into said chamber in a position to be engaged by said piston when said piston is adjacent to one end of its range of movement, said cylinder being provided with a restricted passageway providing communication between the ends of said plunger. 5
5. In a device of the character described, in combination, a cylinder provided with end walls forming a chamber, a piston operating within said chamber, means for supplying pressure medium to both sides of said piston, a bore in one end wall of said cylinder, a plunger fitted within said bore and extending normally within said chamber, means in said end wall providing a passage from said bore to the chamber, and other means in said plunger providing a second passage for the purposes described. 10
6. In a device of the character described, in combination, a cylinder provided with end walls forming a chamber, a piston operating within said chamber, a bore in one end wall of said cylinder, a plunger fitted within said bore, said plunger adapted to extend normally in the path 15 of the piston, a restricted opening in said wall providing a passage from the bore to the chamber, and a second passage located within said plunger for the purposes described. 20
7. In a device of the character described, in combination, a cylinder provided with end walls forming a chamber, a piston operating within said chamber, a bore in one end wall of said cylinder, a plunger fitted within said bore, said plunger adapted to extend normally in the path 25 of the piston, a restricted opening in said wall providing a passage from the bore to the chamber, means for regulating said opening, a second passage located within said plunger, and a check valve for closing said second passage for the purposes described. 30
8. In a device of the character described, in combination with a cylinder, a piston operating within said cylinder, of an end wall adapted to be fitted to said cylinder, said wall being provided with a bore, a plunger fitted for movement within said bore, a hollow portion provided in said plunger and communicating with said bore, a spring within said bore and hollow portion tending to keep said plunger extended, a passage in said wall communicating with said bore, and a second passage in said plunger communicating with the hollow portion for the purposes described. 35
9. In a turret lathe, in combination with a turret slide, of a turret adapted to be indexed in response to reciprocations of said slide, fluid pressure means for operating said slide comprising, a cylinder, a piston operating within said cylinder, conduits having access to said cylinder to supply a pressure fluid to both sides of said piston, a tubular plunger operating within one end wall of the cylinder, and a check valve on said plunger to prevent rapid escape of the fluid within, to cause a decrease in the speed of the piston in one direction of movement. 40
10. In a fluid pressure mechanism, in combination, a cylinder, a piston operating within the cylinder, conduits connected to the cylinder to admit a pressure fluid selectively to opposite sides 45 of the piston, means mounted for reciprocation between the two ends of said piston. 50
11. In a fluid pressure mechanism, in combination, a cylinder, a piston operating within the cylinder, conduits connected to the cylinder to admit a pressure fluid selectively to opposite sides 55 of the piston, means mounted for reciprocation in one end wall of the cylinder and normally projecting within the cylinder, said means being engaged by the piston in one direction of movement thereof, said cylinder being provided with a restricted passageway providing communication between the two ends of said means. 60
12. In fluid pressure mechanism, in combination, a cylinder having end walls forming a chamber, a piston operating within the chamber, conduits connected to the cylinder to admit a pressure medium selectively to opposite sides 65 of said piston, a bore in one end wall of the cylinder, a plunger fitting in the bore and being resiliently urged in a direction to project within the cylinder, whereby the piston in one direction of movement engages the plunger to force the same within the bore, said cylinder having a restricted passageway providing communication between the ends of said plunger. 70
13. In a fluid pressure mechanism, in combination, a cylinder having end walls forming a chamber, a piston operating within the chamber, conduits connected to the cylinder to admit a pressure medium selectively to opposite sides 75 of said piston, a bore in one end wall of the cylinder, a plunger fitting in the bore and being resiliently urged in a direction to project within the cylinder, whereby the piston in one direction of movement engages the plunger to force the same within the bore, said plunger operating upon the pressure medium when being forced inwardly to cause a decrease in the speed of the piston in that direction, said cylinder having a restricted passageway, providing communication between the ends of said plunger. 80
14. In a device of the class described, in combination with a slide, of fluid pressure means for operating said slide, comprising a cylinder, a piston operating within said cylinder, conduits having access to said cylinder to supply fluid under pressure selectively to the two sides of said piston, and a plunger located in said cylinder at one side of said piston adapted to be moved by said piston when said piston is adjacent to one end of its stroke, said cylinder having a restricted passageway providing communication between the two ends of said plunger to cause a decrease in speed of said piston adjacent to said end of the movement of said piston, said plunger being provided with a check valve for providing less restricted communication between the ends of said plunger when fluid under pressure is admitted to that side of said piston adjacent to said plunger. 85
15. In a device of the class described, in combination, a movable member, fluid pressure means for operating said member, said fluid pressure means including a cylinder, a piston operating therein, conduits having access to said cylinder to supply a fluid under pressure selectively to the two sides of said piston, a plunger journaled in a 90

- wall of said cylinder at one side of said piston adapted to be moved by said piston when said piston is adjacent to one end of its stroke, said cylinder having a restricted passageway providing communication between the two ends of said plunger, and adjustable means for varying the extent of restriction of said passageway.
16. In a device of the class described, in combination, a cylinder, a piston operating within said cylinder, conduits connected to said cylinder to communicate fluid under pressure selectively to opposite sides of said piston, a plunger journaled within a wall of said cylinder, a check valve for permitting ingress of fluid to one side of said plunger during one direction of movement of said piston, and other means to regulate the escape of said fluid during movement in the opposite direction thereof.
17. In a device of the class described, in combination, a cylinder, a piston operating within said cylinder, conduits connected to said cylinder to supply fluid under pressure selectively to opposite sides of said piston, said piston and a wall of said cylinder having cooperating plunger parts for causing a decrease in the speed of said piston during a portion of the travel of said piston in one direction, said wall of said cylinder being provided with a restricted passageway for permitting communication to the two sides of said plunger parts.
18. In a device of the class described, in combination, a cylinder, a piston operating within said cylinder, conduits connected to said cylinder to supply fluid under pressure selectively to opposite sides of said piston, said piston and a wall of said cylinder having cooperating plunger parts for causing a decrease in the speed of said piston during a portion of the travel of said piston in one direction, said wall of said cylinder being provided with a restricted passageway for permitting communication to the two sides of said plunger parts, said plunger parts being provided with a check valve for permitting communication between the two sides of said plunger parts during the other direction of movement of said piston.
19. In a device of the class described, in combination, a cylinder, a piston operating within said cylinder, conduits connected to said cylinder to supply fluid under pressure selectively to opposite sides of said piston, said piston and a wall of said cylinder having cooperating plunger parts for causing a decrease in the speed of said piston during a portion of the travel of said piston in one direction, said wall of said cylinder being provided with a restricted passageway for permitting communication to the two sides of said plunger parts, and adjustable means for controlling the extent of restriction of said restricted passageway.
20. In a device of the class described, in combination, a cylinder, a piston operating within said cylinder, conduits connected to said cylinder to supply fluid under pressure selectively to opposite sides of said piston, said piston and a wall of said cylinder having cooperating plunger parts for causing a decrease in the speed of said piston during a portion of the travel of said piston in one direction, said wall of said cylinder being provided with a restricted passageway for permitting communication to the two sides of said plunger parts, said plunger parts being provided with a check valve for permitting communication between the two sides of said plunger parts during the other direction of movement of said piston, and adjustable means for controlling the extent of restriction of said restricted passageway.

WILLIAM H. FOSTER.
